Patented July 26, 1921.

Inventor
Harry E. Palmer
By Geis' Scoville
Attorney

UNITED STATES PATENT OFFICE.

HARRY E. PALMER, OF BURLINGTON, VERMONT, ASSIGNOR TO AUTO SPECIALTY CO. INC., OF BURLINGTON, VERMONT, A CORPORATION OF VERMONT.

LICENSE-HOLDER.

1,385,949.

Specification of Letters Patent. Patented July 26, 1921.

Application filed July 5, 1919. Serial No. 308,796.

To all whom it may concern:

Be it known that I, HARRY E. PALMER, a citizen of the United States, residing at Burlington, county of Chittenden, State of 5 Vermont, have invented certain new and useful Improvements in License-Holders, of which the following is a specification.

This invention relates to a case or frame for holding automobile licenses, registration 10 cards and the like. My invention contemplates an article which is to be attached in some convenient place in an automobile truck or the like where it can be readily inspected by the traffic officer and yet at the 15 same time be removable so that when a car is left standing it may be quickly detachable and carried on the person or put in place of safety where it can not be tampered with by unauthorized parties.

20 The utility of such device will be apparent to all those familiar with automobile requirements and the habits of drivers. The advisability of having at all times when driving the licenses and registrations required by law has made it highly desirable to keep such papers in the car itself. The difficulty has been that the papers must be kept where they can be readily inspected by an officer and yet where they can not be maliciously or accidentally defaced, lost or removed.

30 The difficulty of meeting these requirements is a source of constant annoyance to the automobile and an equally constant basis for embarrassing warnings, arrests or revocations of license by the authorities.

35 My invention contemplates a device by which these papers may be safely and conveniently preserved permitting their habitual location and permanent display in the vehicle itself and yet also permitting them to be readily removed and slipped in the pocket where a car is temporarily left in a public place.

40 For the purposes of illustration of my invention I have shown in the accompanying drawings a form of device found well adapted to use and to the usual requirements and average habits of motorists. In this form 45 the invention comprises essentially a permanent base or back plate which is attached to the car and a detachable frame or case within which these papers may be lodged in such a way as to be visible, this case or frame

being capable of an immediate snug mounting on the base or back and yet readily detachable and conveniently carried in the pocket when so desired. 55

Throughout the specification and drawings like reference characters are correspondingly employed, and in the drawings:

Figure I is a view of the blank constituting my frame member.

Fig. II a plan view of the back member.

Fig. III a vertical section between front 65 and back of my assembled device, and

Fig. IV an enlarged vertical section through the assembled member at right angles to that of Fig. III.

In constructing my invention I produce a 70 sheet metal blank as shown in Fig. I, consisting of generally rectangular piece having a central cut out or opening through which the license or registration card is to be exposed.

The stock from this cut or opening constitutes a base 1 which is provided with screw holes 3 for permanently attaching it to some convenient portion of the car. The top edge of the base member 1 is bent over 80 in a hooked portion 2 and at its lower edge is turned at right angles to form a flange 4 the material being inturned upon itself to make a strong resilient lip. This lower lip or flange is cut away at 5 to give finger 85 clearance.

The frame blank consists of main top and bottom areas 10 and side areas 11 beyond which are edge areas 12 and 13 at the top and side respectively. These areas are 90 adapted to be bent backwardly along the lines 12¹ and 11¹ indicated in dotted lines in Fig. I to form the edges of the frame.

Beyond the area 13 which constitutes the lateral edges of the frame are back flaps 14 95 which in turn are folded along dotted lines 14¹ shown in Fig. I. These flaps 14 are notched as indicated at 15 leaving between the notches a tongue 16 which is slightly bent out of the plane of the rest of the flap 100 so as to be disposed somewhat behind it and readily engageable by the top hook portion 2 of the base member 1. The bottom area 12 is notched at 17 to leave a central thumb tab 18 for engagement when it is desired to 105 dislodge the frame from the base member. When the frame member shown in Fig. I is thus bent up it comprises substantially a

complete frame having a rectangular opening in the front and partially inclosed on the sides of the back. This permits the assembly within the frame of a cardboard back B which is held in place by the flaps 14, a license or registration card L and a transparent protecting sheet C preferably of celluloid or the like.

The frame member if detached may be immediately attached or mounted on the base member by pushing the tongues 16 up under the hook portion 2 of the back and then pushing in on the base of the frame until the lower edge portions 12 snap within the lower lip 4 of the base 1.

The portions of the lip 4 of the base 1 adjacent the opening 5 are slightly sprung or pressed inwardly as indicated at 51 in some exaggeration. This causes the frame to be tightly gripped by the base on each side of the tab 18 thus holding the frame securely in place and yet making it readily releasable by a slight prying pressure.

The frame with the license fully protected and neatly bound may therefore be detached or attached. When attached the license is plainly visible through the celluloid C requiring only a glance from the officer if the driver is stopped in traffic. The structure of the base member and its engagement with the frame member makes it possible to use the blank struck from the front opening of the frame thus giving a piece of satisfactory dimensions and thus saving scrap.

Various modifications may obviously be made in the construction and utilization of my device, all without departing from the spirit of my invention if within the limits of the appended claims.

What I therefore claim and desire to secure by Letters Patent is:

1. A license card holder, comprising the combination of a flat rectangular metal plate having provisions for permanently attaching it to a supporting surface, one edge of said plate being folded over and the opposite edge being bent at substantially right angles, and an open metal frame of greater length than said plate and having its edges folded over to hold the card, the folded portions of the longitudinal edges of said frame being cut away near one end so as to engage under said folded over edge of the plate, the end folded edge of said frame remote from said cut away portions being adapted to detachably engage said bent edge of the plate, and said end folded edge of the frame and said bent edge of the plate being centrally cut away to facilitate their disengagement.

2. A license card holder, comprising a base plate and a removable frame, said base plate having two opposite parallel edges bent over and said frame having all four edges bent over, two parallel bent edges of

said frame being notched to engage under one of the bent over edges of said base plate and one of the remaining edges of said frame detachably fitting under the other bent edge of said base plate.

3. An automobile license card holder, comprising an open metal frame having its edges folded over to hold the card, and a base plate formed from the center portion of said frame and having two parallel edges bent over, the said bent edges being adapted to removably engage certain of said folded edges, whereby the base plate may be permanently attached to a supporting surface of an automobile and the frame be mounted on said plate or be detached therefrom and carried in the pocket of the driver.

4. An automobile license holder comprising the combination of a flat sheet metal plate flanged on two opposite edges and provided with holes by which it can be permanently secured to a supporting surface, and an open sheet metal frame flanged on its edges to hold the license card, said frame being longer in one direction than said plate and having its longer flanges notched near one end to engage one of the flanges on the plate, one of the shorter flanges of said frame being adapted to engage the other flange on the plate, said two last mentioned flanges being centrally cut away to facilitate the disengagement of the frame from the plate, said frame also having a finger piece at said cut away portion.

5. A device of the class described comprising a permanent attachable base having a hooked top and flanged bottom and an open frame, comprising a cut out front portion, folded side portions and inturned back flap portions, said back flap portions of said frame being slotted to receive said hooped top and said frame bottom snugly fitting with said flanged bottom.

6. A sheet metal article of the class described consisting of a frame member and a base member, said frame consisting of a folded blank comprising a rectangular front area having an opening therethrough, edge areas formed on the edges of the front area and back flap areas formed on the edges of opposite edge areas, said base member comprising the blank from said front area opening and having its top and bottom edges bent into frame engaging members.

7. An automobile license holder, comprising a relatively flat folded blank having a front area provided with a display opening therethrough and having overfolded marginal portions defining with said front area a pocket underlying said display opening and adapted to receive and position an inserted license registration for inspection through said display opening, and a relatively flat base underlying said blank and adapted to be permanently attached to an

automobile and having its opposite edges bent to provide blank engaging portions whereby said blank may be detachably mounted upon said base.

5 8. A holder of the class described, comprising a base and a frame detachably connected to each other, and having respectively a finger opening and a finger tab registering with said opening when the base and frame 10 are assembled whereby the frame may be detached from the base by simple pressure applied to said finger tab followed by a withdrawing pull thereon.

9. In a device of the class described, a 15 frame having a finger pull, a base comprising

ing a blank cut from said frame having a finger opening registering with said finger pull when the base and frame are assembled whereby the frame may be detached from the base by simple pressure on the finger 20 tab followed by a withdrawing pull thereon, and an interlocking connection between the frame and base.

In testimony whereof I affix my signature in presence of two witnesses.

HARRY E. PALMER.
